UNITED STATES PATENT OFFICE.

FRANK FONTNEAU, OF ATTLEBOROUGH, MASSACHUSETTS, ASSIGNOR TO
P. J. CUMMINGS & CO., OF SAME PLACE.

COMBINED SMOKER'S MATCH-BOX AND CIGAR-TIP CUTTER.

SPECIFICATION forming part of Letters Patent No. 642,520, dated January 30, 1900.

Application filed February 28, 1899. Serial No. 707,192. (No model.)

To all whom it may concern:

Be it known that I, FRANK FONTNEAU, a citizen of the United States, residing at Attleborough, in the State of Massachusetts, have 5 invented a new and useful Improvement in a Combined Smoker's Match-Box and Cigar-Tip Cutter, of which the following is a specification.

The object of my invention is to provide a 10 convenient cigar-tip cutter in connection with a suitable box for carrying matches in the pocket of the smoker; and it consists in the combination of the cover of the box with a perforated cutter-plate jointed to the cover 15 and sliding between two parallel perforated plates secured to the back of the body of the box, as hereinafter fully set forth.

In the accompanying drawings, Figure 1 represents a side view of a match-box provided 20 with my improvement, the box being shown in its opened condition. Fig. 2 represents the same with the box closed. Fig. 3 represents an edge view. Fig. 4 represents a top view with the cover raised as in Fig. 1. Fig. 5 represents a side view of the sliding 25 perforated plate of the cigar-tip cutter.

In the accompanying drawings, A represents the body of the match-box, preferably made in oblong form, as shown in Fig. 4, the 30 cover B being hinged thereto at the point c, a projecting spur d and a spring e being provided, as usual, to properly hold the cover in its opened or closed positions. To the ears f, at the upper rear corner of the cover, is jointed 35 the plate g, provided with the perforation h, having a beveled cutting edge i, and also

with the slot j. The rear edge of the body A of the box is provided with the parallel plates k k, each provided with a beveled perforation l, the perforated plate g being arranged to 40 slide between the said plates k k, and the said perforations l l and h being made to register with each other when the cover B is in its opened condition, as shown in Fig. 1, and out of register therewith, as shown by the dotted 45 circle h in Fig. 2, when the cover is in its closed position. The perforated plate g is held between the plates k k by means of the pin m, which passes through the slot j. When the cover B of the box is opened to the position shown in Fig. 1 and the tip of a cigar inserted into the registered perforations l l h and the cover B forced down to the closed position, as shown in Fig. 2, the tip will be severed from the body of the cigar. 50

I claim as my invention—

The combination of the body of the match-box, with the parallel plates at the back of the box provided with the opposite perforations beveled at their upper edges, the sliding 60 plate pivotally jointed to the cover and held between the said parallel plates and having a perforation beveled at its lower edge, and registering with the perforations of the parallel plates when the cover is in an opened 65 condition, and adapted to cut off the tip of the cigar upon the closing movement of the cover, substantially as described.

FRANK FONTNEAU.
